UNITED STATES PATENT OFFICE

RICHARD W. BEACH, OF NOBLESVILLE, INDIANA,

DESIGN FOR A PAPER NAPKIN OR SIMILAR ARTICLE

Application filed January 16, 1932. Serial No. 42,513. Term of patent 3½ years.

To all whom it may concern:

Be it known that I, RICHARD W. BEACH, a citizen of the United States, residing at Noblesville, R. R. #6, in the county of Hamilton and State of Indiana, have invented a new, original, and ornamental Design for Paper Napkin or Similar Article, of which the following is a specification, reference being had to the accompanying drawing, forming part thereof.

The figure of the drawing is a plan view of approximately one-fourth of a napkin or similar article indicated in dotted lines, the other three corners bearing the same design but arranged in proper relation to the detailed illustration to complete the napkin or similar article.

I claim:

The ornamental design for a paper napkin, or similar article, as shown and described.
